J. A. DOBLE.
FUEL BURNER.
APPLICATION FILED FEB. 14, 1918.

1,332,616.

Patented Mar. 2, 1920.

UNITED STATES PATENT OFFICE.

JOHN A. DOBLE, OF SAN FRANCISCO, CALIFORNIA, ASSIGNOR TO DOBLE LABORATORIES, OF SAN FRANCISCO, CALIFORNIA, A CORPORATION OF CALIFORNIA.

FUEL-BURNER.

1,332,616.

Specification of Letters Patent.

Patented Mar. 2, 1920.

Application filed February 14, 1918. Serial No. 217,077.

To all whom it may concern:

Be it known that I, JOHN A. DOBLE, a citizen of the United States, and a resident of the city and county of San Francisco, State 5 of California, have invented a certain new and useful Fuel-Burner, of which the following is a specification.

The invention relates to liquid fuel burners and particularly to burners of the rotary 10 type.

An object of the invention is to provide a fuel burner in which the fuel is readily ignited, particularly when an electric spark is employed as the ignition means.

15 Another object of the invention is to provide a fuel burner in which the fouling of the spark producing means by carbon or other accumulation is prevented.

A further object of the invention is to 20 provide a fuel burner wherein the ignition means is arranged in the fuel mixture stream, but is shielded from direct contact with the high velocity fuel mixture passing through the burner.

25 A further object of the invention is to provide means for causing a substantially perfect fuel mixture to contact with the ignition means.

The invention possesses advantageous features, some of which, with the foregoing, will be set forth at length in the following description, where I shall outline in full, that form of the invention which I have selected for illustration in the drawings accompanying and forming part of the present specification. In said drawings I have shown one specific form of my invention, but it is to be understood that I do not limit myself to such form, since the invention, as 35 expressed in the claims, may be embodied in a plurality of forms.

Referring to said drawings:

Figure 1 is a horizontal section of the burner taken on the line 1—1, Fig. 2.

40 Fig. 2 is a vertical section of the burner taken on the line 2—2, Fig. 1.

Fig. 3 is a horizontal section of the ignition chamber, taken on the line 3—3, Fig. 2.

45 Fig. 4 is a vertical cross section of the ignition chamber taken on the line 4—4, Fig. 3.

Fig. 5 is a side elevation of the disk entrance side of the ignition chamber.

50 In fuel burners, in which the air for combustion is blown into or through the burner,

the velocity of the fuel mixture passing through the burner is high and difficulty has been experienced in igniting the mixture by an electric spark. In accordance with my invention I provide a zone which is protected from the draft of air through the burner and arrange the ignition means in this zone with the effect that ignition is effective and instantaneous. Ordinarily two electrode spark plugs have heretofore been employed for 60 producing the ignition spark, but I have found that spark plugs of this description readily become fouled with carbon, so that the required spark is not produced. This difficulty is eliminated in the burner of my 65 invention by causing a rotating element to serve as one terminal of the spark gap.

The burner comprises a casing 2 having an air inlet opening 3 and a flame discharge outlet 4. The air inlet is preferably formed 70 as a neck 5 depending from the casing, the neck serving as the container for the motor 6 and its shaft 7. Secured to the motor shaft and disposed within the casing, is a rotatable disk or cup 8, the side wall 9 of 75 which is inclined upwardly, so that the fuel is discharged from the periphery of the disk in a fine spray. The fuel is fed through the nozzle 12 into a depression at the center of the cup, whence it is impelled outwardly 80 and over the edge of the cup. Secured to the shaft 7 below the cup is a blower 13 which operates to draw air through the inlet 85 passage and force it up past the periphery of the cup, where it mixes with the discharging spray.

Arranged on one side of the casing 2 is an ignition casing 25 forming an ignition chamber having a bottom wall 14 which terminates in a curve lying adjacent the lower 90 part of the wall 9 of the disk, so that air from the blower is prevented from being blown directly into the ignition chamber. The upper wall 15 of the chamber extends over the periphery of the disk and is provided at its end with a curved depending wall 16, the lower edge of which lies adjacent the surface of the disk. The wall 16 is set at an angle to the periphery of the disk, its leading edge 17 being spaced from the 95 wall 9 and its rear edge 18 lying close to the wall 9, so that a passage of decreasing area in the direction of the movement of the disk, is provided between the walls 16 and 9. Air, or a mixture of air and fuel, is set 100 105 110

in motion by frictional contact with the disk and this air or mixture is forced into the passage, and on account of its decreasing size, is forced over the edge of the 5 wall 9.

The rear wall 19 of the ignition chamber springs from the front wall 23 in a smooth curve and gradually diverges from the wall 9, forming a chamber of increasing size 10 which at its rear end opens into the casing 2. Insulated from the ignition chamber and extending through an aperture in the rear wall 19 is an electrode 21, the forward edge of which lies adjacent the edge of the wall 15 9, which forms the other electrode. When the ignition circuit is closed, ignition sparks bridge the gap between the stationary and movable electrodes and the combustible mixture is ignited and the flame blown into the 20 burner casing, igniting the entire mixture. By providing a rotating electrode, the fouling of the spark gap by accumulated carbon is prevented. This prevention of the fouling of the spark gap is further insured by 25 spacing the electrode 21 from the edge of the disk a greater distance than the edge 22 of the front wall 23, which then acts as a scraper to remove accumulated carbon from the edge of the disk.

30 The mixture of air and fuel, preferably kerosene, distillate or similar fuel, pours over the edge of the wall 9 into the ignition chamber, where it is thoroughly mixed, due to the eddy currents formed, and passes 35 through the spark gap, where it is ignited. The ignition chamber is efficient in operation, causing almost instantaneous ignition of the fuel mixture when starting from an all-cold or heated condition. The front wall 40 23 is preferably arranged tangential to the periphery of the disk or cup and the edge 24 of the upper wall 15 is preferably substantially radially disposed with relation to the cup. This forms a radially-disposed 45 opening through which the combustible mixture enters the ignition chamber and on account of the angularly-disposed wall 16, this mixture is forced over the edge of the cup and through the spark gap, where it is 50 readily ignited. The ignited mixture blows out through the opening at the rear of the chamber and ignites the entire mixture, causing a flame to be blown from the outlet 4.

55 Features of the burner disclosed but not claimed herein are covered in United States Letters Patent No. 1,273,467 issued to applicant and William A. Doble, Jr., on July 23, 1918.

60 I claim:

1. In a liquid fuel burner, rotatable means for producing a fuel spray, means for supplying air to said spray to form a combustible mixture, and an electrode arranged 65 adjacent and spaced from said rotatable

means, said rotatable means serving as the other electrode of an ignition spark gap.

2. In a liquid fuel burner, a rotatable fuel spray producing electrode.

3. In a liquid fuel burner, a rotatable fuel 70 spray producing electrode, a stationary electrode, means for forming a spark between said electrodes, and means for feeding liquid fuel into the rotatable electrode.

4. In a liquid fuel burner, a rapidly rotatable cup from the edge of which liquid fuel is discharged in a spray, means for feeding liquid fuel to said cup, an electrode arranged adjacent the edge of said cup, and an ignition circuit connected to said cup and 80 said electrode.

5. In a liquid fuel burner, a rotatable electrode, means for feeding liquid fuel into said electrode, a stationary electrode arranged adjacent the rotatable electrode, and 85 a casing inclosing the stationary electrode and extending over the edge of the rotatable electrode.

6. In a liquid fuel burner, a rotatable electrode for producing a fuel spray, means for 90 supplying air to said spray to produce a combustible mixture, a chamber closed on the side adjacent the incoming air and arranged to receive said spray, and a stationary electrode in said chamber.

7. In a liquid fuel burner, a rotatable cup for producing a fuel spray, means for supplying air to said spray to produce a combustible mixture, a casing partly overlying said cup, a wall on said casing depending into said cup and forming with the wall of the cup a chamber of decreasing area, and an electrode arranged within said casing.

8. In a liquid fuel burner, a rotatable electrode for producing a fuel spray, a stationary electrode arranged adjacent said movable electrode, and means for removing deposited carbon from that portion of the rotatable electrode adjacent which the stationary electrode is arranged.

9. In a liquid fuel burner, a rotatable electrode and a stationary electrode between which an ignition spark is formed, and means for preventing the accumulation of carbon on the rotatable electrode.

10. In a liquid fuel burner, a rotatable cup for producing a fuel spray, a casing partly overlying said cup, a bottom wall on said casing terminating adjacent the periphery of said cup, a front wall on said casing terminating adjacent the periphery of said cup, a top wall on said casing extending over said cup, and a wall depending from said top wall into the cup, the forward end of said depending wall being 120 spaced from the end of said front wall.

11. In a liquid fuel burner, a rotatable cup for producing a fuel spray, a casing partly overlying said cup, a wall on said casing arranged within said cup and dis- 130

posed to produce with the side wall of the cup, a chamber of decreasing area, and means in said chamber for producing an ignition spark.

5. 12. In a liquid fuel burner, a rotatable element from which the fuel is discharged in a spray, means for blowing air past the periphery of said element, a wall arranged adjacent the periphery and shielding a portion

10 of the periphery from said moving air, ignition means arranged on the lee side of said wall, and a depending wall arranged within the periphery of the element for directing the combustible mixture to said ignition

15 means.

13. In a liquid fuel burner, a rapidly rotatable electrode, means for feeding liquid fuel onto said electrode wherefrom it is discharged by centrifugal force in a spray, and

20 a stationary electrode arranged adjacent said rotatable electrode.

14. In a liquid fuel burner, a rotatable cup-shaped electrode from which fuel is discharged in a spray, a casing partly overlying the electrode, a stationary electrode arranged within the casing adjacent said rotatable electrode, and means for directing the combustible mixture from the cup over the edge thereof and through the gap be-

25 tween the electrodes.

15. In a liquid fuel burner, a rotatable

electrode, and a stationary electrode between which an ignition spark is formed, and means for preventing carbon from bridging the gap between these electrodes. 35

16. In a liquid fuel burner, a cup-shaped electrode arranged to be rapidly rotated about its axis, and means for feeding liquid fuel into the electrode.

17. In a liquid fuel burner, a cup-shaped 40 electrode, means for feeding liquid fuel into the electrode, means for axially rotating said electrode to discharge the liquid fuel therefrom in a spray, and a stationary electrode arranged adjacent and spaced from 45 said cup-shaped electrode, whereby an ignition spark may bridge the gap between the electrodes.

18. In a liquid fuel burner, a cup-shaped electrode, means for continuously feeding 50 liquid fuel into said electrode, means for axially rotating said electrode at high speed whereby the fuel is discharged from the edge thereof in a spray, and a stationary electrode having its end lying adjacent the 55 discharge edge of the rotating electrode.

In testimony whereof, I have hereunto set my hand at San Francisco, California, this 4th day of February 1918.

JOHN A. DOBLE.

In presence of—
H. G. PROST.
